UNITED STATES PATENT OFFICE.

WILLIAM L. BEALL, OF CHATTANOOGA, TENNESSEE, ASSIGNOR TO INTERNATIONAL HARVESTER COMPANY, A CORPORATION OF NEW JERSEY.

CANE MILL.

Application filed August 17, 1925. Serial No. 50,539.

This invention relates to crushing mills and particularly to cane mills having a nest of crushing rollers between which the stalks are guided and fed, to extract the juice therefrom.

It is the main object to provide in such a machine an arrangement of crushing rollers so constructed that they will properly receive and feed the stalks in a manner best conducive to the attainment of a maximum extraction of juice.

Another object is to provide a novel form of feeding roller which cooperates with an improved relatively stationary guiding member for the stalks.

Still another object is to prevent objectionable winding of the stalks around the shafts carrying the rollers and also to overcome breakage in the stalks which occurred heretofore in conventional mills. Stalk breakage is objectionable because loose matter falls into the juice.

These, and other objects, which should be apparent to one familiar with this art, are accomplished in the provision of a cane mill, as hereinafter disclosed, having a body in which is mounted a plurality of shafts, each of which carries a roller. One roller is a main or primary roller and cooperable therewith is a secondary roller between which the stalks are fed. A finishing roller also cooperates with the primary roller. The primary roller has its surface provided with spiral grooves or corrugations pitched in one direction while the finishing roller has the same surface grooves, but pitched in an opposite direction. The secondary roller is provided with fluted portions arranged substantially at right angles to the grooves on the main roller, the latter having flanges so that the secondary roller may operate therebetween. Cooperating raised portions on the stationary guide member and secondary roller are also provided. All of these features combine to make an efficient crushing mill because the stalks are properly fed and guided while being crushed.

In the accompanying sheets of drawings, wherein like characters of reference denote like parts, and wherein the preferred embodiments of the invention have been illustrated,—

Fig. 1 is a side elevation of the mill with that part of the body or housing nearest the observer removed. The finishing roller also has been removed;

Fig. 2 is a plan sectional view of Fig. 1 taken along the line 2—2, looking in the direction of the arrows;

Fig. 3 is an end view of the nest of rollers when looking at Fig. 2 from right to left, the main roller being partly broken and,

Fig. 4 is a detail sectional view showing the rolling contact of the secondary feed roller with the relatively stationary guide member, as viewed along line 4—4 of Fig. 2; looking in the direction of the arrows.

Referring now to the sheet of drawings, there is shown a cane crushing mill having a body or frame 10 in which is suitably journaled a vertically disposed shaft 11, which carries thereon a primary or main feeding and crushing roller 12, the shaft carrying fixed therewith above the roller 12 a gear 13. The body also carries a vertical shaft 14 rotatably journaled therein, upon which is carried a secondary or supplementary feed roller 15 of a diameter considerably smaller than the diameter of the main feeding roller. Adjacent the shaft 14 there is journaled a similar shaft 16 in the body of the mill, and this last mentioned shaft carries a finishing roller 17 of substantially the same diameter as the secondary roller. The upper end of the shaft 14 is provided with a gear 18 meshing with the gear 13, and the shaft 16 is provided at its upper end with a similar gear, not shown, so that rotation of the shaft 11 may be imparted to the shaft 14 and the shaft 16 from the gear 13, as will be obvious. The rollers 15 and 17, as shown in Fig. 2, are slightly spaced apart and receive between them a vertically disposed, relatively stationary guide member 19, which has upper and lower projections 20 and 21 loosely fitted into apertures in the upper and lower parts of the body or frame 10. The guide has a concave surface, as shown in Fig. 2, which is slightly spaced from and concentric with the main feeding roller 12.

This disposition of three rollers and a guide member, so far described, is quite conventional in this art. Applicant has, however, improved upon the construction of these rollers to the end that they cooperate in a more efficient manner to crush cane stalks and extract juice therefrom. Referring to Figs. 1 and 3, it will be seen that the large, main roller 12 has on its sides, flanges 22, and that the surface of the roller is provided with fine corrugations in the form of spiral grooves,

and that these grooves have a uniform pitch in the same direction. The supplementary crushing and feed roller 14 is also of a peculiar configuration, and it will be observed that its surface is provided with fluted portions 23 which extend side by side around the surface thereof parallel with the axis of rotation of the roller, and, furthermore, that these fluted portions stop short of the ends of the roller 10 to provide raised, smooth portions 24 at its ends. These fluted portions 23 are formed by cutting out or dishing out the surface of the roller, and it has been found that the high portions of these fluted portions firmly grip 15 a stalk of cane when it is fed between this roller and the main roller and feed the same into the machine without breaking the stalk. It will be noted that these fluted portions are disposed substantially at right angles with 20 respect to the spiral grooves on the main roller 12 and also that the roller 15 in its cooperation with the roller 12 operates between the flanges 22 of said roller 12.

Looking now to the roller 17, it will be observed that it also cooperates with the roller 12 and that it too has its surface provided with fine corrugations, or spiral grooves, similar to those on the surface of the roller 12, but that these spiral grooves are pitched in an 30 opposite direction from those on the roller 12. This is an important feature of the invention, for, it will readily be appreciated (Fig. 2), that as the stalk of cane is fed between the main roller and the supplementary roller it 35 is guided by the guide 19 between the main roller and the finishing roller 17, where the oppositely pitched, grooved surfaces function to oppose each other in feeding the bagasse in a spread condition across the center 40 of both rollers, thus overcoming any possibility that the bagasse might spread over the edge of the rollers and wind around the shaft 16. Going back to the supplementary feed or fluted roller 15, the raised portions 24 also 45 serve properly to guide the incoming stalks toward the center, as the stalks cannot readily pass upwardly or downwardly beyond the raised portions 24, formed by closing the ends of the fluted portions 23, and in this instance 50 also preventing the possibility of the crushed stalk passing over the ends of the roller and winding around the ends of the shaft 14.

The guide 19 also embodies improved features, which make for efficient operation of 55 guiding and crushing the stalks of cane fed into the machine. Attention in this connection is directed to Fig. 4, which shows the face of the guide member adjacent the main feeding roller depressed as at 25 with an upraised flange portion 26 at each end, which cooperates with the supplementary feed roller 15, the upraised portions 24 of which have a rolling contact with these raised portions 26. Obviously, then, the end face of the guide 19 60 is slightly spaced from the fluted portions on

the roller 15. By this construction it is impossible for the fluted portions of the roller 15 to contact the corrugations on the main feeding roller and, therefore, neither can injure the other.

The construction of the feed roller 15 is such that stopping the flutes near the end of the feed roller and having the roll smooth at the ends, as at 24, there is, as has been stated, a tendency of the cane to work away from the flanges 22 of the large roll 12 as it is being fed through the mill. This is illustrated in a somewhat exaggerated manner in Fig. 3. The advantage gained by this construction of feed roll is considerably 70 helped by the arrangement of the depressed member, or knife, as it is sometimes called, as shown in Fig. 4. The mill is at a disadvantage with conventional guide knife members because the cane mashes in between the 75 ends of the feed roll 15 and the flanges of the large roll 12. The feed roll in its operating position is spaced about 1/8 or 1/4 of an inch away from the large roll and the construction of this feed roll with the raised or smooth ends makes it permissible to employ a guide member that will not catch on the corrugations or flutes of the roll 15. At the same time, the guide member will at all 80 times be close enough to the feed roll throughout its entire length to perform its guiding function efficiently without mashing the stalks against the flanges 22, as stated.

It is to be understood, of course, that only the preferred embodiment of this invention 90 has been shown and illustrated and that the same is capable of many modifications and changes without departing from the spirit of the invention and the scope thereof as hereinafter claimed.

What is claimed is:

1. In a cane mill or the like, having a body, a main feeding roller journaled for rotation in the body, a supplementary feed roller also journaled for rotation in the body, said supplementary roller being fluted longitudinally on its surface, said flutes being continuous and stopping short of the ends of said roller.
2. In a cane mill or the like, the combination of a body, a feeding roller rotatable 115 therein of uniform diameter and provided with depressed fluted portions which stop short of the ends of the roller to form smooth portions, and a guide member having smooth end portions, said roller raised portions bearing on and having a rolling contact with the raised portions of the guide member.
3. In a cane mill having a plurality of rotatable crushing rollers, one of said rollers having its surface provided with continuous 120 fluted portions parallel with the axis of rotation of the roller, said portions stopping short of the ends of the roller.
4. In a cane mill having a plurality of rotatable crushing rollers, one of said rollers 125

having its surface provided with relatively deep, continuous fluted portions parallel with the axis of rotation of the roller, said fluted portions being closed at their ends to leave 5 smooth marginal end surfaces for the roller.

5. In a cane mill, the combination of a main feed roller, a fluted supplemental feed roller and a finishing roller cooperating with the main roller, a stationary guide between 10 the fluted and finishing rollers, and cooperating flanges on the guide and fluted roller to provide a rolling contact for the fluted roller on the guide member.

6. A roller for cane mills, said roller having 15 uninterrupted, relatively deep, fluted por-

tions extending lengthwise thereof, said fluted portions terminating short of the ends of said roller.

7. A roller for cane mills, said roller having 20 its surface provided with spaced, parallel, continuous fluted portions extending lengthwise thereof, said fluted portions terminating short of the ends of said roller.

8. A roller for cane mills, said roller having 25 smooth circumferential ends on its surface and continuous fluted portions arranged side by side in parallelism between said smooth end surfaces.

In testimony whereof I affix my signature.

WILLIAM L. BEALL.
